Primary Examiner — Derrick Holland*Assistant Examiner* — Lauren Calve*(74) Attorney, Agent, or Firm* — Dentons US LLP(57) **CLAIM**

The ornamental design for a welding power supply grill, as shown and described.

DESCRIPTION

FIG. 1 is a perspective view of the design for a welding power supply grill;

FIG. 2 is a front view of the design for the welding power supply grill of FIG. 1;

FIG. 3 is a right side view of the design for the welding power supply grill of FIG. 1;

FIG. 4 is a left side view of the design for the welding power supply grill of FIG. 1;

FIG. 5 is a top view of the design for the welding power supply grill of FIG. 1;

FIG. 6 is a bottom view of the design for the welding power supply grill of FIG. 1; and,

FIG. 7 is a rear view of the design for the welding power supply grill of FIG. 1.

The broken lines shown represent unclaimed subject matter and form no part of the claimed design.
